UNITED STATES PATENT OFFICE.

CHARLES L. GOEHRING, OF ALLEGHENY, PENNSYLVANIA.

THILL-COUPING.

SPECIFICATION forming part of Letters Patent No. 224,422, dated February 10, 1880.

Application filed December 17, 1879.

To all whom it may concern:

Be it known that I, CHARLES L. GOEHRING, of Allegheny, in the county of Allegheny and State of Pennsylvania, have invented certain new and useful Improvements in Thill-Couplings; and I do hereby declare the following to be a full, clear, and exact description of the invention, such as will enable others skilled in the art to which it pertains to make and use it, reference being had to the accompanying drawings, which form part of this specification.

My invention relates to thill-couplings, and is an improvement on my invention for which a patent was granted me by the United States, dated December 23, 1879, No. 222,819.

It consists in securing the coupling-bolt more effectively by means of an appliance to the lever on the cam and on the head of the bolt, as will be fully described hereinafter.

It also consists in the use of a stop to prevent the cam from being moved too far in the wrong direction.

The accompanying drawings represent my invention.

Figure 1 is a plan view. Fig. 2 is a similar view, partly in section. Fig. 3 is a vertical section, and Fig. 4 a detail view.

a represents the axle; *b*, the clip; *c*, the shackle; *d*, the coupling-bolt, and *e* the thill-iron. All of these parts may be constructed in suitable manner and be of any form desired.

The shackle *c* may be entirely closed on top and bottom by the plates *g*, so as to form a box where a finely-finished coupling is preferred; or the inner edges at both top and bottom may be provided with the flanges *i*, which extend horizontally inward toward the center, but which are only wide enough to form guides to hold the spring in place as it is moved back and forth. The shackle with these flanges can be much more easily made, as they can be struck up in the dies, whereas the plates *g* require to be specially fastened on.

The cam is made flat on its rear side, and operates to push a spring forward against the thill-iron, and is provided with a handle or lever, *l*, by means of which the cam is turned in its bearings in the shackle. The holes through the shackle in which the ends of the cam are held are made longer than is simply necessary

to allow the cam to turn, for the purpose of allowing the ends a slightly-forward movement, so that the backward pressure of the spring will cause the cam to snap into position when so turned that the full pressure of the spring is brought to bear against it, and thus the cam will be held against accidental displacement.

The rounding or front edge of the cam, when turned forward, bears against the sliding plate *n*, which has the two horizontal flanges *o* secured to its top and bottom edges. Between these two flanges is secured to the plate a metallic spring, *r*, which entirely incloses the rubber block or spring *s* on its rear, top, and front edges, and partially on its bottom. The front side of this spring *r* is made concave to correspond with the shape of the thill-iron, and serves to protect the rubber from contact with its rear end. This spring may either bear directly against the rear end of the thill-iron, or there may be a thin plate interposed between them, as may be preferred. This spring adds resistance to the rubber spring, and prevents the rubber from becoming worn by friction against the thill-iron, and thus assists the rubber in maintaining a constant and even pressure, which cannot be done where the gum spring is not thus protected. The rivet *v*, which secures the spring to the plate, projects through on the back of the plate, and acts as a stop to prevent the cam from being turned downward past its proper position.

The cam being journaled in oblong holes or slots in the shackle, it is at liberty, when it is turned by means of the hand-lever so as to exert its pressure against the spring, slightly to shift its axis from a straight to a diagonal line until the projection on the lever drops into a corresponding slot in the head of the bolt, when it is pushed back to its former position by the spring. The deviation from a straight line occurs when the cam-lever is brought down outside on the head of the coupling-bolt, and ceases when the lever has reached this point, where it is held either by a cavity conforming to the head of the bolt or by a projection on the lever entering a slot in the head of the bolt. The cam-lever then presses upon the head of the coupling-bolt, locks and confines it, by the resistance of the spring and india-rubber com-

bined, against the cam in the rear and the thill-iron in front, and cannot be removed without the application of a suitable key.

When the cam-lever is to be raised up or removed from the head of the coupling-bolt to uncouple the thill, an outward pressure by means of the key should precede or accompany the upward motion in order to lift it from its resting-place by overcoming the pressure of the metallic and rubber springs.

Instead of two springs, as here shown, a single rubber spring will act in the same manner, and it is the pressure of this spring which locks the lever on the bolt-head.

Having thus described my invention, I claim—

1. The sliding plate *n*, having a stud, *v*, on its rear side, to act as a stop to the cam, substantially as shown.

2. The combination of the cam having a lever attached thereto, a spring, thill-iron, and coupling-bolt, the lever being provided with means whereby it will lock itself on the head of the bolt, substantially as specified.

In testimony that I claim the foregoing I have hereunto set my hand this 9th day of December, 1879.

C. L. GOEHRING, M. D.
